UNITED STATES PATENT OFFICE.

GEORGES MICHOT, OF DROMARA, IRELAND, ASSIGNOR TO THE FIBRE CORPORATION, LIMITED, OF LONDON, ENGLAND, AND MARSHALL SONS AND COMPANY, LIMITED, OF GAINSBOROUGH, ENGLAND.

FLAX-PULLING MACHINE.

Application filed March 6, 1923. Serial No. 623,282.

To all whom it may concern:

Be it known that I, GEORGES MICHOT, a citizen of the Swiss Republic, and residing at Dromara, County Down, Ireland, have 5 invented certain new and useful Improvements Relating to Flax-Pulling Machines, of which the following is a specification.

This invention relates to flax-pulling machines of the type described in British Patent specification No. 153,115, its object being 10 to simplify the comb-cleaning means of such machines.

The invention broadly consists in providing a pivotally mounted cleaning bar 15 adapted to follow the motion of the comb teeth so that the cleaner remains close to or in contact with the comb teeth and cleans them from end to end as each comb passes the said bar.

20 In order that the carrying of the invention into effect may be understood, reference may now be made to the accompanying drawings, in which:—

Figure 1 is a side elevation of the machine; 25 Figure 2 is a plan view, and

Figure 3 an end view of the machine showing in detail the serrated edges of the cleaning device.

In carrying the invention into effect in 30 one form, I provide a frame, A, made in one nominally rigid structure adapted to support the road-wheel axle, B, and the comb-carrying device, hereinafter referred to in detail. At the rear end of the machine are 35 curved swinging links or hangers, C, attached to a shaft, D, mounted within bearings, E, which are fixed in a suitable position on the frame, A, of the machine. The hangers, C, carry at their lower ends cleaning bar, F, preferably having a serrated edge and extending across the comb-carrying 40 part of the machine. The comb pins, G, are carried by a member, H, supported on rigid arms, J, extending from chain belts, K.

45 The latter co-operate with the chain wheels, L₁, L₂, the rear chain wheels, L₁, being driven from the road wheels, M, through suitable gearing, N, and a clutch, O. The chain wheels, L₂, situated at the forward 50 end are in the particular machine illustrated in the drawings of smaller diameter than the aforesaid chain wheels, L₁, although the diameters of the wheels may, according to circumstances, be in any desired relation.

ship to each other. The bearings, P, of the 55 shaft, Q, carrying the chain wheels, L₂, at the leading end are preferably adjustably fastened to the frame, A, so that the tension of the chain belts, K, may be adjusted. The linear speed of the chain belts, K, relative to 60 the frame, A, is less than the relative speed of advance of the machine, the difference between the said speeds being the speed of advance of the combs, G, through the crop. The teeth of the combs are made of 65 rectangular or other suitable section of material and shaped at their ends remote from the comb-carrying brackets in such manner as to facilitate their entry into the standing crop. Provision is made for the 70 prongs of the combs, G, to enter the standing crop at the most suitable angle and this may, for example, be effected by hinging, as shown at S, or otherwise adjustably fastening the draft pole, S₁, to the frame, A. 75

The arms, J, carrying the combs, G, are provided at their upper ends with an element, U, adapted to co-operate with the guide rails, R, and with a roller, V, for contacting with the hangers, C. By providing 80 the roller, V, upon the comb-carrying bracket, J, for contacting with the back of the hangers, C, strains on the combs, G, are relieved and the cleaning bar, F, follows the movements of the combs, G, arising 85 from the motion of the links of the chain-belt around the chain wheels, L₁. In operation, each comb, G, carried on its pivot links passes the cleaning bar whose edges traverse the teeth and thus sweep away any 90 adhering material. The hangers, C, are controlled by springs, W, or the like in such manner that the cleaning bar, F, carried by them is pulled towards the approaching 95 combs, G. The motion of the cleaning bar, F, is preferably limited by a stop, C₁, which ensures correct position of cleaner bar, F, to meet next comb.

The position of the comb-carrying device may be adjusted relatively to the road-wheel axle. This is effected, for example, by attaching a lifting bracket, X, to the bearing, B₁, of the main axle, B, and providing a sliding member, Z, therein suitably fastened to the frame, A, of the machine 100 and an adjusting screw, X₁, working within the lifting bracket, X. The axle bearings, B₁, are retained in position by horn blocks 105

or bearing brackets formed integral with or suitably fastened to the frame, A. To relieve the whole weight of the machine from the screw, X_1 , a locking pin, X_3 , is provided for inserting in the holes, X_2 , in the lifting bracket, X, and the frame, A.

Having now described my invention, what I claim as new and desire to secure by Letters Patent is:—

1. A flax-pulling machine having comb teeth comprising a pivotally mounted cleaning bar adapted to follow the motion of the comb teeth so that the cleaner remains close to or in contact with the comb teeth and

cleans them from end to end as each comb passes the said bar. 15

2. A flax-pulling machine as set forth in the preceding claim, in which a chain belt is employed and in which the said cleaning bar, is preferably serrated, and carried by 20 hangers adapted to prevent the combs being strained and to cause the cleaning bar to follow the movement of the comb arising from the motion of the links of the chain-belt.

In testimony whereof I have signed my 25 name to this specification.

G. MICHOT.
